UNITED STATES PATENT OFFICE.

JOHN L. BOGERT, OF FLUSHING, NEW YORK.

GOVERNOR FOR STEAM-ENGINES.

SPECIFICATION forming part of Letters Patent No. 307,835, dated November 11, 1884.

Application filed May 8, 1884. (No model.)

To all whom it may concern:

Be it known that I, JOHN L. BOGERT, of Flushing, in the county of Queens and State of New York, have invented an Improvement 5 in Centrifugal Governors for Steam-Engine Eccentrics, of which the following is a specification.

In steam-engines heretofore constructed the eccentric has been movable automatically by 10 the centrifugal action of a weight, in order that the movement of the valve and the point at which the steam is cut off may be varied by shifting the center of the eccentric nearer to or farther from the axis of the main shaft in 15 an imaginary line, called the "lap and lead line."

The object of my invention is to simplify the construction of the parts, and to sustain 20 the eccentric by parallel-motion bars connected at equal distances from the center of the eccentric, so that the center of such eccentric will be moved in a straight line, and this will be effected automatically according to the speed at which the engine is running.

25 In the drawings, Figure 1 is an elevation of the eccentric and the mechanism connected with the same, and Fig. 2 is a sectional plan view of the same.

The shaft A is rotated by the engine, and 30 the wheel W is fastened thereon. The eccentric E is of any desired size, and it is provided with an elongated opening for the shaft A to pass through. The eccentric E is made with arms that extend out from the back part 35 in opposite directions, as at M M, and one of these arms is prolonged and terminates as an enlargement or weight. These parts are made integral with the eccentric. The parallel-motion bars R R' are pivoted at B B' to the arms 40 S of the wheel W. The pivots B B' are preferably made as pins passing through holes in the arms and secured to the bars R R', respectively, by clamping-nuts, the pins turning in the holes in the arms S. The parallel-motion 45 bars are connected to the arms M M by the pivot-bolts q q, and the opposite end of the bar R' is connected by the pivot-bolt u to the spring G in any suitable manner. I have, however, shown a counter-weight, C, in the 50 shape of a bow, through which the pivot-bolt

u passes, and to one end of which counter-weight C the spring G is fastened, and at the other end of said counter-weight C there is a link, D, to the end of the bar R. The spring G is connected at one end and adjusted by 55 the bolt v, that passes through the wheel W or a projection thereon, and at p there is a buffer of rubber or similar material around the counter-weight C, to stop against the projection o on the wheel W, and thereby lessen 60 noise when the parts come into contact, as they are liable to do when sudden changes occur in the load upon the engine. It will now be apparent that the spring G, acting upon the bar R', moves the eccentric E to the greatest 65 distance from the axis of the shaft A, and that the valve of the engine that is actuated by the eccentric and its rod will receive the largest amount of motion and admit steam to the engine with but little cut-off action. As 70 the speed of the engine increases, the weight N will be thrown off by the centrifugal action and cause the center of the eccentric to approach the axis of the main shaft, and when the maximum speed is attained the motion of 75 the valve will be only twice the lap, and no steam will be admitted. In the intermediate positions the cut-off will be in proportion to the speed. Under all circumstances the bars R R' will act with the eccentric similar to a 80 Watts parallel motion, and the center of the eccentric will move toward and from the axis of the shaft in a straight line.

It will be apparent that the counter-weight C and link D might be omitted; but when 85 used the counter-weight C acts centrifugally, as well as the weight N, to give motion to the eccentric.

Any suitable spring may be applied as a resistance to the centrifugal force; but I prefer 90 the helical spring shown.

I claim as my invention—

1. The combination, with the shaft A, wheel W, eccentric E, and weight, of the parallel-motion bars R R', the latter of which forms a 95 lever, and the tension-spring G, connected at one end to the lever-bar R' and at the other end to the governor-wheel, substantially as set forth.

2. The combination, with the eccentric E, 100

of the parallel-motion bars R R', connected to such eccentric, the counter-weight C, the spring G, and the link D, connecting the counter-weight to the outer end of the bar R, substantially as set forth.

3. The combination, with the pivoted parallel-motion bars R R', of an eccentric, arms upon that eccentric, and a weight, all integral with the eccentric, and a spring, substantially as set forth.

4. The combination, with the eccentric and

the pivoted parallel-motion bars R R', of the spring, the counter-weight C, connected to the bar R and to the spring, the link D, between the counter-weight C and bar R, and the means 15 for adjusting the tension of the spring, substantially as set forth.

Signed by me this 5th day of May, A. D. 1884.
JOHN L. BOGERT.
